(57) **CLAIM**

The ornamental design for a portable airplane tray cover, as shown and described.

DESCRIPTION

FIG. 1 is a back view of the portable airplane tray cover of the present invention.

FIG. 2 is a top view of the portable airplane tray cover of the present invention.

FIG. 3 is a front view of the portable airplane tray cover of the present invention.

FIG. 4 is a side view of the portable airplane tray cover of the present invention.

FIG. 5 is a top perspective view of the portable airplane tray cover of the present invention.

FIG. 6 is a bottom perspective view of the portable airplane tray cover of the present invention.

FIG. 7 is a top perspective view showing the removable liner of the top portion of the portable airplane tray cover of the present invention; and,

FIG. 8 is a bottom perspective view showing a bottom grip surface of the portable airplane tray cover of the present invention.
